FLUE FORMING ELEMENT FOR SKILLETS

Pauline Dake Mitchell, Athens, Tenn.

Application March 24, 1952, Serial No. 278,241

1 Claim. (Cl. 220—4)

1

This invention relates to a flue forming element mountable upon a skillet for preventing grease from spattering onto the stove or onto the person while using the skillet for cooking.

An object of the present invention is to provide a flue forming element which is made of flexible material and which is removably mountable upon a skillet.

Another object of the present invention is to provide a flue forming element which is simple of structure and commercially feasible.

Other objects of the present invention and advantages will become apparent from the following description taken in conjunction with the accompanying drawing wherein.

Figure 1 is a plan view of the flue forming element of the present invention.

Figure 2 is a perspective view showing the flue forming element of the present invention mounted upon a skillet.

Figure 3 is a plan view of the assembly of Figure 2.

Referring to the drawing, the numeral 10 designates the flue forming element of the present invention, such element being fabricated of a one piece strip of flexible material such as heavy absorbent material, foil or like material, and being in the shape of a horseshoe as shown in Figure 1, said horseshoe strip lying in a plane. Integrally connected to and projecting from the portion of the inner bounding edge 11 of the horseshoe shaped element or strip 10 on one side of the longitudinal median line A—A of the element are at least two spaced tabs 12 and 13. As the structure of the tabs is the same, only one will be specifically described. The tab 12 is of a button shape but having a straight side 14 nearest the adjacent free end 9 of the element 10. Extending inwardly from the straight side 14 of the tab 12 adjacent its connection to the inner edge 11 of the element 10 is a slot 15. Also, integrally connected to and projecting from the portion of the inner edge 11 of the element 10 on the other side of the longitudinal median line A—A of the element 10 are at least another two spaced tabs 16 and 17. Since each of the latter tabs is the same structurally only one will be described in detail. Tab 16 is likewise of a button shape but having a straight side 18 remote from the adjacent free end 19 of the element 10, and extending inwardly from the straight side 18 of the tab 16 adjacent its connection to the inner edge 11 of the element 10 is a slot 20.

The flue forming element 10 is removably mountable upon a skillet. By reference to Figures 2 and 3 it will be seen that the slot 20 of the tab 16 interlocks with the slot 15 of the tab 12,

2

resulting in the conversion of the element 10 into a flue, and that such flue embraces and rests removably upon the top of a skillet 21 and the adjacent portion of the handle 22 projecting exteriorly from the skillet. With the element 10 connected together as above pointed out to form a flue, the air and fumes from the cooking pass freely through the flue but preventing the grease from spattering onto the stove or onto the person using the assembly for cooking.

After use, the flue is readily lifted from the top of the skillet 21, and may then be employed to wipe the stove and to remove the grease from the skillet.

15 By interlocking the slot 15 of the tab 12 with the slot 20 of the tab 17 or the slot 15 of tab 13 with the slot 20 of tab 16, the element 10 forms a flue of a size to embrace and rest removably upon the top of a skillet of a smaller size than 20 that of skillet 21.

I claim:

A flue forming element for a skillet comprising a one piece strip of flexible material and shaped in the form of a horseshoe, said horseshoe strip 25 lying in a plane, at least two spaced tabs integrally connected to and projecting from the portion of the inner bounding edge of said horseshoe strip on one side of the longitudinal median line of the horseshoe strip, and at least another 30 two spaced tabs integrally connected to and projecting from the portion of the inner bounding edge of said horseshoe strip on the other side of said median line, each of said tabs being formed with a slot adjacent its connection to the inner 35 edge of said element, a slot of one of the tabs on one side of said median line being selectively interlockingly engageable with the slot of one of the tabs on the other side of said median line to thereby form a flue for embracing and resting 40 upon the top of a skillet.
